STOKER

Verdrie F. Clark, New Albany, Ind., assignor to
Peerless Manufacturing Corporation, Louis-
ville, Ky.

Application June 18, 1938, Serial No. 214,552

1 Claim. (Cl. 198—64)

This invention relates to stokers and more particularly to an improved stoker construction whereby the connections between the hopper and the retort are such that there will not be any misalignment between the hopper and the retort in order that the rotary conveyor in the form of a screw will freely operate in the tubular connection between these parts.

An object of this invention is to provide in a stoker structure an improved conveyor housing which is so constructed that substantially the full length of the conveyor will be disposed in the housing, the conveyor housing being provided within the hopper with an intake portion which is cut out from the housing so as to permit the coal or other fuel to enter the conveyor housing and be moved therewith by rotation of the screw conveyor.

Another object of this invention is to provide an improved conveyor housing connecting the retort with the hopper structure so as to provide means whereby the retort and the hopper will be held in permanent alignment in order that the conveyor disposed in the conveyor housing will freely operate at all times.

A further object of this invention is to provide an improved conveyor housing which connects the retort and the hopper, the housing being removably secured in the retort and the hopper in order that the housing may be easily removed for replacement or other purposes.

A still further object of this invention is to provide a hopper structure which engages over a trough secured to the conveyor housing with the hopper enclosing the trough forming the bottom of the hopper and secured to the trough in a manner to prevent gases from entering the room in which the stoker is positioned.

With the foregoing objects and others which may hereinafter appear, the invention consists of the novel construction, combination and arrangement of parts as will be more specifically described and illustrated in the accompanying drawings, wherein is shown an embodiment of the invention, but it will be understood that changes, variations and modifications may be resorted to which fall within the scope of the invention as claimed.

In the drawings:

Figure 1 is a detail top plan of a stoker structure constructed according to an embodiment of this invention.

Figure 2 is a detail side elevation partly broken away and in section of the device,

Figure 3 is a fragmentary longitudinal section of the device,

Figure 4 is a sectional view taken on the line 4—4 of Figure 3,

Figure 5 is a sectional view taken on the line 5—5 of Figure 3,

Figure 6 is a fragmentary end elevation of the hopper structure showing the inner end of the conveyor and the means for connecting the conveyor to the reduction gearing,

Figure 7 is a fragmentary sectional view showing the coupling between the reduction gearing and the adjacent or inner end of the conveyor,

Figure 8 is a fragmentary transverse sectional view through the lower portion of the hopper,

Figure 9 is a perspective view of the hopper bottom,

Figure 10 is a detail side elevation of the conveyor housing, and

Figure 11 is an enlarged fragmentary longitudinal section of the upper portion of the hopper showing the hopper closure and the means for sealing the closure on the hopper.

Referring to the drawings, the numeral 10 designates generally a hopper structure and the numeral 11 designates a retort which is adapted to be positioned interiorly of a furnace and the retort 11 is connected to the hopper 10 by means of a conveyor housing 12 and an air duct 13. The hopper 10 comprises a housing 14 provided at its upper side with an intake opening 15 which is defined by an upstanding bead or rim 16. A closure plate 17 having a marginal turned down portion 18 engages about the upstanding bead 16 and a gasket 19 is interposed between the plate 17 and the bead 16 so as to tightly seal the closure 17 on the housing 14. One end of the closure 17 may be hingedly secured to the housing 14 by hinge members 20 adapted to engage beneath the closure 17 and the opposite end of the closure 17 is provided with a locking bolt 21 which is secured to a handle 22 by means of a pivotal member 23.

A trough or hopper bottom member is disposed in the housing 14 and comprises a pair of downwardly inclined walls 24 and 25 which have their lower or convergent edges thereof spaced apart and connected by means of an arcuate channel member 26. The upper or divergent edges of the bottom wall members 24 and 25 are provided with upstanding flanges 27 and 28 respectively. An inner wall 29 is secured to the inner ends of the wall members 24 and 25 and to the flanges 27 and 28 and is substantially rectangular in front elevation and an outer or forward wall 30 is secured

to the opposite ends of the wall members 24 and 25. The inner wall 29 is provided at its upper end with a rearwardly extending flange 29^a and the outer wall 30 is provided at its upper end with an inwardly extending flange 30^a. The inner wall 29 is provided with a bottom flange 31 and the outer or forward wall 30 is provided with a bottom flange 32 extending in the direction of the flange 31. The wall member 29 is provided in substantially the center thereof with a round opening 33 and the wall member 30 is provided with an opening 34 which is arcuate at its lower portion and substantially rectangular at its upper portion.

15 The conveyor housing 12 comprises an elongated tube 37 which is provided with a cut-out portion 38 constituting an intake opening adjacent the inner end thereof which is adapted to be disposed in the arcuate portion 26 of the hopper trough or bottom hereinbefore described. The longitudinal edges 39 of the cutout portion 38 are adapted to be disposed substantially coplanar with the lower or convergent edges of the bottom wall members 24 and 25 so that the coal 20 or other fuel in the hopper will readily enter the intake opening 38 and be moved along the length of the tubular member 37 by a spiral or screw conveyor 40. The tubular member 37 is adapted to be secured to the hopper structure 14, the inner 25 end thereof engaging in a bushing 41 having a flange 42 which is secured as by bolts 43 to the inner or rear wall 29 of the hopper trough.

A clean-out housing 44 having a flange 45 at one end thereof is secured to the forward wall 30 30 of the hopper trough as by bolts 46 and this clean-out housing 44 is disposed about the conveyor housing 12 at a point adjacent the forward end of the intake opening 38. The housing 44 is provided with an opening 47 at its upper side about 35 which a closure plate 48 of arcuate construction engages. A gasket 49 is interposed between the closure 48 and the marginal portions of the opening 47 so as to seal the plate 48 on the housing 44. A closure holding bar 50 is disposed on the upper side of the closure 48 extending entirely 40 thereacross and the rear end of the bar 50 engages in a slot 51 provided in the flange 45 and the forward end of the bar 50 has a bolt 52 engaging therethrough. The bolt 52 has the head 53 thereof secured in the upper portion of the housing 44 and a wing nut 54 is threaded onto the bolt 53 and provides a means for tightly pressing the bar 50 against the closure 48 so as to prevent the escape of gases through the opening 47.

55 The retort structure 11 comprises a plenum chamber 55 engaging about the forward end of the conveyor housing 12, and this plenum chamber communicates with a tuyère structure 56. The tuyère structure 56 is provided with a plurality of air openings 57 communicating with the plenum chamber 55 so that the air from this chamber 55 will enter the tuyère or retort structure. The tuyère structure includes a throat or fuel outlet member 58 having a sleeve 59 engaging about the forward end of the conveyor housing 12. The throat member 58 is provided with a supporting leg 60 engaging the bottom wall 61 of the plenum chamber 55.

70 The plenum chamber 55 has a rear wall 62 and the air duct 13 is connected at one end to the rear wall 62 at one side of the housing 12. The rear wall 62 is provided with a closure plate 62^a which closes an opening at the opposite side from the duct 13 so that the duct 13 can be positioned 75 on either side of the housing 12. The air duct

13 extends below the hopper bottom structure comprising the bottom walls 24 and 25 and the end walls 29 and 30. The rear end of the air duct 13 is connected to the outlet side of a fan structure 63 which is positioned in a chamber 64 provided at the rear of the hopper or housing structure 14. The fan 63 is operated by means of a motor 65 adapted to be connected to a suitable source of current supply. The walls of the chamber 64 are provided with louvers 66 so that air may freely enter the housing or chamber 64 and be forced through the air duct 13 into the retort 11. A reduction gearing generally designated as 67 is disposed in the chamber 64 and is operatively connected to the motor 65 by means of a driving connection 68 in the form of a flexible belt or the like. The construction of this reduction gearing 67 is well known and comprises the usual gear means whereby the number of revolutions of the motor 65 may be reduced sufficiently 20 to provide a relatively slow turning of the conveyor 40. The reduction gearing 67 is provided with a connector or coupling part 69 engaging in the inner end 70 of the conveyor 40.

The clean-out opening 34 in the forward wall 25 of the trough registers with an opening 35 provided in the flange 51 of the clean-out housing 44 so that any pieces of coal which might stop the conveyor 40 may be dislodged. The rear wall 36 of the housing 14 is provided with an inwardly extending flange 71 which rests on the flange 29^a and a gasket 72 is interposed between the flanges 29^a and 71. The flanges 29^a and 71 are secured together as by headed fastening members 73.

The forward wall 71 of the housing 14 is secured to the forward side of the wall 30 by fastening members 78 and a gasket 79 is interposed between the walls 30 and 71. The side walls of the housing 14 project down below the side flanges 27 and 28 of the trough, terminating at the bottom of the walls 29 and 30, as shown in Figure 8, and are secured to the flanges 27 and 28 by fastening members 74. A gasket 75 is interposed between the side walls of the housing 14 and the flanges 75 and may be integral with gasket 79. The side walls of the housing 14 below the flanges 27 and 28 are provided with louvers 76 so that air may enter below the trough.

The bushing 41 is provided with a flange 80 confronting the gearing 67 and this flange 80 is secured to the gearing 67 by means of bolts 81 or the like.

The rear wall 29 of the trough member is provided with a pair of openings 82, one on each side of the opening 33 and the air duct 13 passes through a selected one of these openings 82. The forward wall 30 of the trough is also provided with a pair of duct openings 83 and the duct 13 engages through a selected one of these openings 83 so that the air duct 13 may be positioned on either side of the opening 33. A covering or plate 84 may be bolted over the opening 83 in the wall 30 which is not used whereas the opening 82 in the wall 29 which is not used may be left open so that air from the louvers 76 may pass therethrough into the chamber 64.

The motor 65 is secured to a plate 85 which is supported on a plurality of upstanding studs 83 carried by a bracket 87 secured to the top of the 70 gearing 67. The gearing 67 may be provided with a safety shear pin retaining nut 88.

In the use and operation of this stoker, the fuel in the form of coal or the like is placed in the hopper housing 14 by removing the closure 75

17, and when the motor 65 is operating, the conveyor 40 will force the fuel forwardly through the conveyor housing 12 into the retort 11. Coincident with the rotation of the conveyor 14, the 5 fan or blower 63 will be operated so as to force air through the air duct 13 into the plenum or air chamber 55. In the event any coal particles clog the outlet opening 35 of the hopper 14, such clogging particles may be released by opening 10 the clean-out closure member 48.

Through the provision of a continuous conveyor housing extending from the inner or rear wall of the hopper 14 to a point within the retort 11, the retort 11 will not at any time become out 15 of line with the conveyor so that during the continued use of this stoker the conveyor will at all times freely operate in the conveyor housing, and in the event there is any shifting of the foundation for either the hopper structure or the retort, 20 such shifting of the foundation will not effect a misalignment of the operating parts of the stoker. With a stoker structure of this kind, it will also be possible to support the retort 11 from the hopper structure where the supporting of the retort 25 11 will involve undue changes or additions in the lower portion of the furnace. It will therefore be apparent that the stoker structure hereinbefore described may be constructed as a unit for insertion in a furnace, it being only necessary 30 to remove the lower door of the furnace which is

provided for the removal of ashes and insert the retort 11 through this door opening, while at the same time closing the remaining portion of the opening with a suitable plate or the like.

What I claim is:

In a stoker, a hopper, a flange at the lower end of the hopper, a V-shaped bottom member, a pair of end walls secured to said member, flanges carried by the upper ends of said end walls, means detachably securing the hopper flange to said end 10 wall flanges, an arcuate seat at the convergent lower end of said bottom member, a tubular conveyor housing resting on said seat and projecting from one end wall through and beyond the other end wall, a conveyor in said housing, said housing having an intake opening in the upper side thereof, said opening terminating beyond said other end wall, a clean-out housing about said conveyor housing and that portion of said intake opening projecting beyond said other end wall, 20 a closure for said clean-out housing, said clean-out housing having an upstanding flange confronting said other end wall, a downwardly facing shoulder carried by said upstanding flange, a closure holding bar engaging at one end against 25 said shoulder, and means engaging the opposite end of said bar and said clean-out housing for securing said closure on said clean-out housing.

VERDRIE F. CLARK. 30
